UNITED STATES PATENT OFFICE.

GUSTAF BERGMAN, OF MARLBORO, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,168,470.

Specification of Letters Patent.

Patented Jan. 18, 1916.

Application filed July 3, 1911. Serial No. 636,720.

To all whom it may concern:

Be it known that I, GUSTAF BERGMAN, a citizen of the United States, residing at Marlboro, in the county of Middlesex and State of Massachusetts, have invented certain Improvements in Lasting-Machines, of which the following description, in connection with the accompanying drawings, is a specification, like reference characters on the drawings indicating like parts in the several figures.

This invention relates to lasting machines and more particularly to lasting machines of the "bed" type which employ end lasting mechanisms for the toe and heel.

The present invention, as embodied in a machine of the said type, comprises various improvements in the organization and construction of the toe and heel lasting mechanisms, suggested by practical experience in the use of a machine of this type, as well as in the actuating mechanisms therefor.

It also includes new and improved retarding means for coöperating with the toe wipers and a novel hold down for clamping the shoe and last upon their supporting means together with the provision of novel means for supporting the toe and heel ends of a last.

A feature of the toe lasting mechanism consists in the provision of a carrier for the toe wipers mounted for bodily movement upwardly for imparting upper stretching movement to the wipers and forwardly for carrying the wipers into position for the overwipe and, conveniently, means are provided, arranged to be actuated by this forward movement of the wiper carrier to close the wipers for overwiping the upper into lasted position. This mounting of the wipers is strong and efficient and less complicated than the organization of similar mechanisms in machines heretofore used.

For operating the toe wiper carrier and toe wipers for the updraw and overwipe, in accordance with an important feature of this invention, a single means is provided comprising preferably an eccentric or a cam arranged for continued movement to operate the carrier upwardly and forwardly to produce the updrawing and overwiping movements of the toe wipers and for thereafter pulling the said wipers downwardly for compressing and compacting the over-

lasted upper upon the innersole. The illustrated construction is such that a single train of mechanism operates the wipers for their various lasting movements and, preferably, the toe wipers during all their movements are positively actuated.

Highly important features of this invention consist in various improved arrangements for enabling the position and action of the toe wipers to be adapted readily to lasts of varying sizes and shapes. It is essential that the closing action or throw of the toe wipers should be varied for lasts of different widths and a characteristic of the illustrated embodiment of this invention is the provision of convenient means for adjusting the eccentric or cam bodily for varying the throw of the wipers as desired. Preferably, however, the various subsidiary adjustments of the toe wipers are effected independently of and without disturbing the eccentric. For enabling the wipers to be adapted to lasts of crooked or unsymmetrical formation, means are provided comprising a member arranged to be free to be moved transversely of the machine and shoe during an initial closing and positioning movement of the wipers. The construction is such that, as the wipers, which lie in their initial position below the plane of the shoe bottom, are closed in this positioning movement, the position of each wiper relatively to the adjacent edge of the last is determined by the position relatively to the median line of the machine occupied by the said adjacent edge of the last, the said movable member as soon as one of the wipers engages the adjacent edge of the last being thereby shifted through suitable connections to cause the other wiper to be at once correctly positioned with regard to the last edge adjacent to it. Thereafter, in accordance with another feature of the invention, the said member is automatically locked in adjusted position, insuring that the positioning of the toe wipers thus obtained will be maintained during their subsequent overwiping action.

Other features of the invention include the provision of novel means for enabling the toe wipers to be adjusted for operating upon lasts having a greater or less spring and an arrangement by which the toe wipers and their carrier are mounted to be free to turn about the longitudinal axis of the said

carrier to permit the plane of the acting faces of the wipers to coincide with the plane of the forepart of the last, irrespective of the roll or angular position thereof.

5 In accordance with a still further feature of the invention means are provided through which pressure may be applied to the ends of the toe wipers to enable the wipers during their downward compressing movement to crowd the upper hard upon the sole and to compact it in lasted position. Preferably, also, provision is made for imparting a yielding quality to this downward compacting movement of the wipers.

10 15 In accordance with a further important feature of my invention, novel retarding means are provided for coöperating with the toe wipers. These means comprise preferably a yielding member adapted to be brought by manual means into engagement with the upstanding upper at the end of the toe to hold the upper upon the wipers during the updraw, and an associated plate arranged to engage the upper at the corners of the toe. This latter member is unyielding and serves as a stop for limiting the movement of the yielding member. The yielding member engages the upper with spring pressure and during the updraw the 20 25 30 pressure of the said yielding member is automatically increased by compression of its spring. Thereafter, during the overwipe, the corner plate acts as an auxiliary retarder to reduce the undesirable fullness of the upper at the sides of the toe produced by the swinging and backward movements of the wipers in the overwipe. Preferably also the yielding central plate is arranged to have a less curvature than the toe end of the shoe 35 40 45 so that it exerts a spreading action upon the upper at the toe with the result that the wipers are aided in drafting the vamp forwardly along the sides of the shoe. Further drafting of the vamp forwardly along the sides of the shoe is produced by the fact 50 that this yielding member does not partake of the inward or closing movements of the wipers so that during the overwipe the wipers have a forward drawing effect upon the vamp.

Still other features comprise improved means for jacking the shoe at the toe and heel and for independently securing the toe and heel supports in any desired position.

55 A novel hold down is also provided, arranged to be brought into clamping engagement with the sole by treadle controlled means arranged so that the pressure exerted by the hold down can be varied at will 60 and the hold down then secured in engagement with the shoe.

The heel lasting mechanism has in addition to features common to it and to the toe lasting mechanism, improved means for 65 causing the heel supporting band to be con-

formed automatically and snugly to heels of varying sizes and shapes.

These features of my invention hereinbefore noted, as well as other features and characteristics thereof, including certain details of construction and combinations of parts, will be hereinafter fully described and explained in connection with the illustrative embodiment of the invention shown in the drawings, and will then be clearly defined in the appended claims.

Referring to the drawings: Figure 1 shows a machine illustrating one embodiment of my invention; the machine being shown in side elevation; Fig. 2 is a top plan view of the toe lasting mechanism and associated parts, showing the position of the wipers and of their actuating mechanism at the conclusion of the overwipe; Fig. 3 is a detail in side elevation, partly in section, showing the position of the retarding devices prior to the updraw; Fig. 4 is a similar detail in side elevation, showing the position of the parts at the conclusion of the updraw; and Fig. 5 is a top plan view, similar to Fig. 2, of the heel lasting mechanism.

The machine illustrated in the drawings as embodying my invention comprises a bed or frame 2 supported by standards 4. The bed 2 carries in addition to shoe supporting means and associated parts for effecting the jacking of the shoe, the end lasting mechanisms for the toe and heel.

The toe lasting mechanism shown at the left of Fig. 1 is carried by the toe head 6 100 slidably mounted in ways upon the bed 2. The heel lasting mechanism shown at the right of Fig. 1 is carried by a heel head 8 similarly mounted in the said ways. For adjusting the heads 6 and 8 toward and from each other, adjusting screws 10 and 12 are threaded through blocks 14 and 16 of the heads 6 and 8, hand wheels 18 and 20 being provided for turning the said screws for adjusting the respective heads longitudinally 105 of the machine. By means of these adjusting devices, the toe and heel lasting mechanisms can be moved with relation to one another longitudinally of the machine to adapt the said mechanisms for operating upon 110 shoes of all lengths as well as for operating upon shoes having long or short toes or heels.

The toe wipers are supported for upward and for closing or overwiping movements, at one end of a bar 24 (Figs. 1 and 2) which constitutes the carrier for the wipers. This bar 24 has a thickened rectangular portion 26 (Fig. 1) and reduced cylindrical ends. The rounded end 28 of the carrier bar 24 125 is loosely journaled in a bearing block 30 (Figs. 1 and 2) through which extends a pivot pin 32 located in opposite holes 34 of a series of pairs of holes in swinging uprights rising from the toe head 6 and com-

prising thin plates 36 (Fig. 1) pivotally connected to the frame of the said head at 38 to permit tipping or swinging movement of the uprights about the pivot 38 as 5 an axis. The bar 24 is restrained from endwise movement in its bearing 30 by reason of a pin 40 (Fig. 1) and a square shoulder 42 (Fig. 2) formed between the rectangular portion 26 of bar 24, and its rounded end 10 28. The other end of the bar 24 has a similarly reduced and rounded end 44 (Fig. 2) which extends through a bearing block 46 restrained from lengthwise movement relatively to the bar 24 by a pin 47 and a square shoulder 49 on the bar 24. The block 46, in 15 which the end 44 of the bar 24 is thus journaled, is pivotally connected at 48 (Fig. 1) to an upstanding link 50, the lower end of which carries a pin standing in an elongated 20 upright slot 52 in the toe head frame 6. The bar 24 is thus arranged to have bodily movement longitudinally of the machine in a substantially horizontal plane by reason of its aforesaid connection with the uprights 36 25 mounted for swinging movement about their axis 38, and by reason of the pivotal connections at 48 and 52 of the bearing block 46 and the supporting link 50. The bar 24 is also capable of being tipped about the pivot 30 32 as an axis, up and down movement of the forward end 44 of the said bar and its supporting link 50 being permitted by reason of the vertical slot 52. These movements of the bar 24, actuated by mechanism herein- 35 after described, serve to impart the updraw and closing or overwiping movements to the toe wipers in a manner now to be explained.

The toe wipers 54 are of suitable form to embrace the toe end of the last for working 40 the upstanding margin of upper material into lasted position and are pivoted at their inner or rear ends to the rounded end 44 of the bar 24 at 56.

The forward or outer ends of the wipers 45 54 have pin and slot supporting and operating connections at 58 (Fig. 2) with arms 60 of levers 62, the levers 62 being crossed at 64 and there pivoted to the rectangular portion 26 of the carrier bar 24. The wipers 50 are thus mounted to be moved forwardly by the forward or endwise movement of bar 24 and means are provided, arranged to be actuated by the said movement of bar 24 to 55 close the wipers to overwipe the upper into lasted position. To this end the rear ends of the levers 62 are provided with cam slots 65 in which stand cam rolls 66 on a cam roll carrying bar 68 extending transversely of the machine through a slot in the part 26 60 of bar 24. The cam roll carrying bar 68 is restrained from movement lengthwise of the machine by upright guides 70 (Fig. 1) secured to the toe head 6 and having forked upper ends which embrace the said bar 68 65 and permit it to move up and down therein

with the updraw movements of the bar 24. From this construction it will be apparent that upon forward movement of the carrier bar 24 and of the levers 62 which, as above stated, by reason of their connection at 64 70 with the bars 24 are necessarily carried forwardly with the said bar, the cam rolls 66 being stationary relatively to the outwardly and backwardly inclined cam slot 64, will force the rear ends of the wiper closing levers to approach, and consequently the forward ends of the wiper closing levers will be moved toward one another like the blades of a pair of shears. This closing or shearing together of the front ends of the levers 80 62 induced by the forward movement of the bar 24 operates to swing the front ends of the wipers 54 inwardly for overwiping the upper into lasted position, the shoe being supported bottom upward in position for the 85 operation of the wipers thereon.

In addition to the closing or overwiping movements of the wipers, the wipers have imparted to them updraw movement for tensioning and stretching the upper prior to 90 overlaying it in lasted position. This movement of the wipers, like their closing or overwiping movement, is effected by bodily movement of the wiper carrier 24, the wiper carrying end of the bar 24 being swung in 95 a direction substantially perpendicular to the plane of the shoe bottom through tipping of the said bar about its axis 32. By reason of their connection with bar 24 at 56, the wipers 54 are lifted upward by the said upward movement of bar 24. For supporting the front ends of the wipers 54, supporting arms 72 are provided, the rear ends of these arms being secured to the bar 24 and the front ends of the said arms being supported 100 between plates 74 bolted at 76 and 78 to the arms 60 of the wiping closing levers 62 and the said arms 60. The arms 72 enable a firm downward pressure to be applied to the front ends of the wipers to press down 110 and compact the overlasted margin of upper upon the sole and also relieve the joint of the wiper closing levers from excessive strain.

The above described updraw and overwiping movements of the wipers, which as 11 above stated result from upward and forward bodily movements of the bar 24, are preferably actuated from an eccentric 80 (Fig. 1) fixed on a shaft 82 journaled in the upper ends of links 84 which are pivoted to 115 the frame of the toe head 6 at 85. Conveniently a handle 86 is provided for operating the eccentric 80 and shaft 82, although it is obvious that power driven means may be supplied for this purpose, and that for 120 the eccentric 80 a properly designed cam could equally well be substituted. The eccentric 80 as will be seen by reference to Fig. 1 is thus positioned to engage the under side 125 of the part 26 of the wiper carrier bar 24 for 130

lifting the said bar and wipers 54 as above described for imparting updraw movement to the wipers.

For moving the bar 24 forwardly to cause the wipers to be moved into position for the overwipe and then for causing them to be closed for overlasting the upper, the eccentric lies in a forked bracket 88 (Fig. 1) on the supporting link 50, engagement of the eccentric 80 with the face 90 of the link 50 moving the bar 24 and wipers 54 forwardly for the overwipe through the block 46, and engagement of the eccentric with the arm 92 of the bracket 88 operating to move the carrier 84 backwardly and reversely into inoperative position to retard the wipers and to open them after the completion of the toe lasting operation.

After the overwipe of the upper into overlasted position, it is desirable that the wipers be actuated to apply downward pressure to the overlasted upper for compressing and compacting it in order that the upper may be laid snugly upon the sole in its lasted position. To accomplish this, the eccentric 80 is arranged to be brought into engagement with the top of the horizontal portion of the bracket 88 at the conclusion of the inward or overwiping movement of the wipers, thereby positively pushing the carrier 24 downwardly and causing the wipers to exert a strong downward pressure on the overlasted upper. In this connection it should be noticed that, by reason of the above described arrangement of the supporting arms 72, cross arms 60 and plates 74, the wipers are caused to have a particularly efficient compacting action upon the upper through the application of pressure to their ends.

For enabling the throw of the wipers to be varied for adaptation to lasts of different widths, the eccentric shaft 82 lies in elongated slots 94 (Fig. 1) in the toe head frame 6, the said slots being formed to permit bodily adjustment of the shaft and eccentric in a horizontal direction lengthwise of the machine, the supporting links 84 having pivotal connections with the head 6 at 85 as described. Adjusting screws 96 supported in brackets 98 on the head 6 are threaded into lugs 100 on the links 84. Rotation of the screws 96 in one direction operates to force the shaft 82 forwardly in its slots 94, the eccentric 80 thereby through engagement with the face 90 of the link 50 moving the bar 24 forwardly and the wipers inwardly for operating on narrow lasts, and opposite rotation of screws 96 moving the bar 24 and the wipers reversely for operating on relatively wide lasts.

It will be observed that the above described adjustment of the wipers is effected by bodily movement of the eccentric 80 and by its shaft 82. Preferably, however, the va-

rious other adjusting movements of the toe lasting devices are arranged to be effected independently of said shaft and eccentric and without disturbing their normal position.

70

As is well known in the art different lasts vary considerably in the amount of spring of their foreparts. Accordingly, it is essential for satisfactory work that convenient means be provided for adjusting the wipers quickly and accurately to cause the plane of their acting faces to coincide with the plane of the last bottom so that the wipers may overlay the upper evenly and snugly thereon. For so adjusting the wipers, the swing uprights 36 have, as aforesaid, a series of pairs of opposite holes of which the opposite holes 34 are illustrated in Fig. 1 as having extended through them the pivot pin 32 which sustains the bearing block 30 in which is journaled the end 28 of the carrier bar 24. By adjusting the said pin into one or another of these pairs of holes the end 28 of the bar 24 can readily be moved upwardly or downwardly, thereby changing the inclination of the plane of the acting faces of the wipers to conform to the spring of any last.

80

90

Provision is also made for adapting the wipers for operating on lasts of crooked or unsymmetrical formation. If the shoe to be lasted has a crooked last that is, if the median line of the forepart extends in a different direction from the direction of the median line of the heel part, it is obvious that as the wipers are closed, one wiper will engage the upper at the adjacent edge of the last before the other wiper engages the upper at the opposite edge unless provision is made to obviate this difficulty. Accordingly the cam roll carrying bar 68 is arranged to be free to be moved transversely of the machine and shoe in its guides 70. Preferably, in accordance with this feature of my invention, an initial closing of the wipers is effected by movement of the handle 86 to cause the eccentric 80 to move the link 50 forwardly. During this initial positioning of the wipers, the wipers are moved from the open position shown in Fig. 3 inwardly until the edges of the wipers contact with the adjacent edges of the last. Whenever, as the wipers are thus moved inwardly, one of said wipers is stopped by contact with the adjacent edge of the last before the other wiper has engaged the opposite edge of the shoe, the bar 68 will be shifted transversely of the machine, thereby positioning the other wiper relatively to the edge of the shoe bottom adjacent thereto. Thereafter, it is desirable that the wipers should be held relatively to the edges of the shoe in their adjusted position. Consequently the bar 68 is preferably arranged to be automatically locked in adjusted posi-

95

100

105

110

115

120

125

130

135

tion after the initial positioning of the wipers. For this purpose locking hooks or latches 102 (Figs. 1 and 2) are provided on the upper ends of rods 104 guided in bosses 106 secured to the guides 70 and extending through a transverse plate 108 which spans the frame of the head 6 and is secured thereto. These latches are formed with knife edges adapted to be brought into engagement with teeth 110 formed on the upper face of the cam roll carrying bar 68 early in the updraw movement by reason of the lifting of the bar 68 by the carrier 24 as the said carrier is moved upwardly. Thereafter, and until the completion of the lasting operation, the bar 68 is locked against movement transversely of the machine and shoe. A yielding quality is however imparted to the downward compressing movements of the wipers by the provision of springs 112 coiled around rods 104. Confining nuts 114 at the lower ends of the rods 104 are adapted to be turned to adjust the tension of the springs and stop nuts 116 are positioned above plate 108 to limit downward movement of the latches and insure their release from the bar 68 at the proper stage in the cycle of operations of the machine. The springs 112 normally tend to draw the bar 68 downwardly in the guides 70 but permit it to be raised slightly against the tension of said springs sufficiently to permit of the full extent of the upward movement of the wipers and to impart a yielding quality to their downward movement.

In order to accommodate the action of the wipers to the plane of the last forepart irrespective of the angular position of the shoe and last, the wiper carrier 24, as before stated, is journaled at its ends in the blocks 30 and 46. This mounting of the bar 24 permits the said bar and the wipers to turn freely about the longitudinal axis of the bar and thereby allows the wipers to accommodate themselves to the roll of the last.

For supporting the shoe and last in position for the operation of the lasting device, a toe rest and a heel support are provided. The toe rest may conveniently comprise a pad 118 (Fig. 1) of a suitable shape to fit the toe of the shoe upper and secured to a plate 120 fixed upon the upper end of a post 121 as by the straps 122. The post 120 is supported for vertical adjustment in a bearing block 124 rising from an extension of the toe head 6. The lower end of the post 120 rests upon an adjusting screw 126. The screw 126 is threaded into the bearing 124, and is arranged to be turned by means of a hand wheel 128 to adjust the post 120 and pad 118 to any desired height.

For supporting the heel end of the last a

last pin 130 (Fig. 1) is pivoted at 132 to the upper end of a post 134. The post 134 is supported for vertical movement in a bearing block 136 secured by bolts to the bed of the machine. The lower end of the post 134 rests upon a rounded cam face formed upon the upper end of an operating lever 138 fulcrumed by means of a pivot pin 140 carried in a yoke 142 slidingly mounted on bracket arms 144 depending from the bed 2. The yoke 142 rests upon a set screw 145. Adjustment of the said screw 145 operates to adjust the yoke 142 vertically on the arms 144 to move the post 134 up or down to regulate the normal or inoperative position of the last pin 130. A coiled spring 146 secured at one end to a hook on a bar 148 depending from the bearing block 136 and fixed at its other end to a hook on the lever 138 normally tends to raise the outer end of said lever and thereby to maintain the post 134 and pin 130 in lowermost or inoperative position. For jacking the shoe the post 134 and pin 130 are raised into operative position by lowering the end of lever 138 against the tension of the spring. In order that the heel post and last pin may be secured in a raised or operative position the depending bar 148 is notched and a beveled plate 149 secured to the lever 138 is adapted to be brought into engagement with one or another of the ratchet teeth on the bar 148 thereby locking the lever 138 in any desired position.

In some work it is desirable to employ a hold down to clamp the shoe and last upon their supporting means. For this purpose preferably a lever 150 (Fig. 1) is fulcrumed at 152 upon an upright standard 154 secured to the bed 2 of the machine. The free end of the lever 150 is adapted to engage the forepart of the inner sole, when the shoe is jacked in position for the operation of the lasting devices to hold the shoe and last firmly upon their supports. The other end of lever 150 is pivotally connected to a treadle rod 156 (Fig. 1) arranged to be operated by a treadle 158 pivoted upon a stand 160 resting upon the floor. Downward movement of treadle 158 operating to raise the rod 156 and the arm of the lever 150 connected thereto, causes the free end of lever 150 to be lowered into engagement with the inner sole of the shoe, as shown in Fig. 2 while the lever 150 is returned to its inoperative position by upward movement of the treadle 158. Conveniently, the stand 160 has an upright rising therefrom and provided with notched teeth 162 adapted to be engaged by the treadle 158 to permit the hold down to be brought into engagement with the shoe with any suitable pressure and then locked in such engagement.

To coöperate with the toe wipers in the

6

lasting operation I have devised an improved retarding device, best shown in Figs. 3 and 4, which comprises a central member 164 and a corner plate 166. The central member 164 preferably comprises a curved blade adapted to bear with its relatively thin edge upon the inner side of the outstanding upper material at the end of the toe to hold the upper upon the wipers. The corner member 166 preferably comprises a relatively wide plate adapted to extend transversely of the shoe to bear with its ends upon the upper materials at the corners of the toe and carried at the lower end of a rod 167 adjustably secured to a lever 170. The blade member 164 is secured to the lower end of a post 168 which extends upwardly through a hole in the lever 170. The post 168 has fixed to it above the lever 170 a washer 172 and the upper end of the said post is confined by a set screw in a bar 174, the front end of which embraces a pin 176 rising from the lever 170. The lever 170 has its free end 178 suitably formed 25 as an operating handle, and is pivoted at its other end to the rectangular portion 26 of the wiper carrier bar 24 (Fig. 1). The lever 170 is thus permitted to be swung upward when not in use, shouldered portions 30 180 (Fig. 1) sustaining the lever in its said incipative position. Preferably, a spring 182 encircles the post 168, the said spring being confined between the lever 170 and a washer on the post 168 above the blade 164. 35 The member 164 is thus brought to bear upon the upper with spring pressure, the spring serving automatically to increase the amount of pressure with which the blade 164 clamps the upper upon the wipers.

40 In the use of the above described retarding device, upon depression of the handle 178 and lever 170, the blade 164 engages the upper at the end of the toe and holds it yieldingly upon the wipers during the updraw, the path of the blade 164 during the 45 updraw and overwipe being indicated by the arrow in Fig. 3. The corner plate 166 acts by rigid engagement with the upper at the corners of the toe as a stop for limiting 50 the downward movement of the blade 164. During the updraw, the upward movement of the wipers forces the blade 164 upwardly against the tension of the spring 182 with the result that the clamping pressure of the 55 blade 164 is thereby automatically increased as the updraw progresses. The member 164 remains in engagement with the upper during the closing or overwiping movement of the wipers but does not of course partake 60 of this closing movement. Consequently the wipers have a forward drawing effect which results in drafting the vamp forwardly along the sides of the shoe. It should also be noticed that the curvature of

the member 164 is considerably less than 65 that of the end of the toe, as clearly shown in Fig. 2. As a result, the said member has a spreading action upon the upper which materially assists the drafting of the vamp 70 along the sides by the wipers during their upward movement. The corner member 166 is lifted by the wipers in the updraw and continues to hold the upper upon the wipers 75 during the overwipe. By reason of the mounting of this supporting lever 170 upon the bar 24 the corner member is advanced with the wipers. The wipers however, as they are moved forwardly, swing inwardly. This inward swinging movement has a sufficient backward component to produce an 80 undesirable fullness at the sides of the toe. The member 166 does not partake of this backward movement, and consequently it has a retarding action during the overwipe 85 which serves materially to reduce the fullness at the sides of the toe. The corner member 166 also projects outwardly at either end beyond the edges of the shoe so that it has a substantial spreading action 90 which aids the above described side drafting of the vamp.

The heel lasting mechanism is in most respects like the toe lasting mechanism hereinbefore described and is substantially similar in its mode of operation. The heel 95 wipers 184 (Fig. 5) are pivoted at 186 to the forward end of a carrier bar 188 mounted for upward tipping and forward bodily movements in precisely the same way in which bar 24 of the toe lasting mechanism is 100 supported. Supporting arms 190 secured to the bar 188 at their rear ends have a bearing at their free ends between arms 192 of wiper closing levers 194 and under plates bolted to the said arms. The wiper closing 105 levers 194 have at their rear ends cam slots 196 in which lie cam rolls 198 on a cam roll carrying bar 200 extending transversely of the machine through a slot in the bar 188 and restrained from movement longitudinally of the machine by upright guides 202 on the heel head 8.

The cam roll carrying bar 200 is however fixed against movement transversely of the machine and shoe by stops 204, the substantial uniformity of the heel portions of shoes with respect to the direction of their median lines rendering it unnecessary that the bar 200 should have the equalizing function of the cam roll carrying bar 68 of the toe lasting mechanism. The carrier bar 188 and the carrier wipers 184 are actuated to engage and overwipe the upper into lasted position over the heel seat by the cam 206 (Fig. 1) on a shaft 208 adapted to be brought successively into engagement with a link 210 which supports the bearing for the forward end of the bar 188 and with a bracket 212

on the said link, the bracket 212 being substantially like the bracket 88 of the toe lasting mechanism.

The heel supporting band 214 has its ends 5 passed around the free ends of links 216 (Fig. 5) pivoted to plates 218 on the wiper closing levers 194, the said ends of the band being secured to springs 220 hooked at their outer ends to the arms 192. These springs 10 tend to draw the ends of the heel supporting band outwardly, thereby causing the band to adapt itself to embrace snugly heels of varying contours and sizes.

In the use of the machine herein shown 15 and described as embodying my invention, the last with the shoe thereon is jacked with the toe resting upon the toe rest pad 118, and the heel part supported by the last pin 130. The hold down is then brought into 20 firm engagement with the inner sole of the shoe. The toe wipers are next adjusted, if necessary, to accommodate themselves to the spring of the last by passing the pivot pin 32 through the proper pair of holes 34, and 25 the eccentric 80 is adjusted lengthwise of the slot 194 to adapt the throw of the wipers to the width of the sole. After this preliminary adjustment the handle 86 is moved from its initial position through an arc re- 30 versely to its general direction of rotation as indicated by the arrow Fig. 1 and substantially to the position shown in Fig. 1 for initially positioning the wipers as heretofore explained. This movement of the 35 handle 86 operates the eccentric 80 to engage the part 90 of the supporting link 50 thereby inducing forward movement of the bar 44 and wipers 54. By this movement the wipers, which lie, in their initial 40 position, below the plane of the shoe bottom, are partially closed and, through the equalizing movement of the cam roll carrying bar 68, the wipers are positioned relatively to the adjacent edges of the last. The upper 45 around the toe is then drawn upwardly over the wipers, usually by hand grippers, and the retarder is swung downwardly to clamp the upper upon the wipers both at the end and at the corners of the toe, the plate 166 50 limiting the movement of the yielding member 164. The eccentric 80 having been returned to its initial position by rotation of the handle 86 in the direction of the arrow Fig. 1, during which movement the eccentric 55 is brought to bear against the arm 92 of the bracket 88 thereby opening the wipers again, the handle 86 is given further continued movement in the direction of the arrow for initiating the updraw. This movement of 60 the handle 86 causes the eccentric 80 to engage the underside of the part 26 of the carrier 24 whereby the carrier and wipers are lifted upwardly. During the first part of the updraw, the cam roll carrying bar 68 is

lifted sufficiently to be locked in its adjusted 65 position against movement transversely of the machine and shoe through engagement of its teeth 110 with the locking hooks 102. Upon further rotation of the handle 86 in the same direction, the eccentric 80 engages 70 the part 90 of the link 50 thereby causing the carrier 24 and wipers 54 to be advanced for the overwipe. The wipers 54 are then swung inwardly for overwiping the upper into lasted position, the retarder, which is 75 all the time held firmly upon the upper, serving, as hereinbefore explained, to facilitate the lasting action of the wipers. After the completion of the overwipe, continued rotation of the handle 86 and eccentric 80 80 in the same direction results in bringing the eccentric to bear against the curved bottom portion of the bracket 88, whereby the carrier 24 is tipped downwardly about its axis and the wipers are positively pulled down- 85 wardly upon the overlasted upper for compressing and compacting it in lasted position. With the lasting devices held in this position, the operator secures the upper in 90 its lasted position by binding wire or other temporary fastenings and the handle 86 is then returned to its initial position, the wipers being lowered, retracted, and opened, and the lasting instrumentalities being then ready for another operation. The lasting of 95 the heel proceeds in a similar fashion, the heel wiper carrying bar being actuated through its operating cam to advance the wipers for engaging the upper around the heel and carrying the upper forwardly and 100 inwardly into position to receive permanent tacks.

It should be understood that the foregoing is merely a description of one convenient embodiment of my invention, shown 105 and described simply by way of illustration, and that I do not thereby limit myself to the precise details of construction herein set forth, since many changes and modifications thereof, such as will readily occur to 110 those skilled in the art, may obviously be made without departing from the spirit and scope of my invention.

Having thus fully described one illustrative embodiment of my invention, what 115 I claim as new and desire to secure by Letters Patent of the United States is:

1. A lasting machine having, in combination, toe embracing wipers, a carrier for the wipers relatively to which the wipers 120 have closing movement, said carrier being mounted to permit upward and forward swinging movement, means for swinging said carrier forwardly, and means to effect closing movement of the wipers by said 125 swinging movement.

2. A lasting machine having, in combination, toe embracing wipers, a carrier rela-

tively to which the wipers have closing movement, a pivot about which said carrier can swing upwardly, a pivot about which the carrier can swing forwardly, and means 5 acting upon the wipers during said forward movement to effect closing movement of the wipers.

3. A lasting machine having, in combination, toe embracing wipers, a carrier relatively to which the wipers have closing movement, a support in which the rear end of the carrier is pivoted for movement of the wipers up and down, and means on which the support is pivoted below the 10 carrier for movement of the wipers forwardly and backwardly.

4. A lasting machine having, in combination, toe embracing wipers, a carrier relatively to which the wipers have closing movement, a support in which the rear end of the carrier is pivoted for movement of the wipers up and down, means on which the support is pivoted below the carrier for movement of the wipers forwardly and backwardly, and an eccentric embraced by 20 parts connected with the carrier to effect said movements of the wipers.

5. A lasting machine having, in combination, toe embracing wipers, a carrier relatively to which the wipers have closing movement, a support in which the rear end of the carrier is pivoted for movement of the wipers up and down, means on which the support is pivoted below the carrier for 30 movement of the wipers forwardly and backwardly, and operating means to impart to the wipers through the said carrier and connections an updrawing movement, then an advancing movement and finally a downward movement.

40 6. A lasting machine having, in combination, a wiper carrier supported for upward and forward movements, wipers supported by the carrier, means for closing the wipers arranged to be actuated by forward movements of the carrier, and a single means for moving the carrier upwardly and then forwardly to impart successively updraw and closing of overwiping movements to the 45 wipers.

50 7. A lasting machine having, in combination, a lasting head, uprights rising from the head, a wiper carrier having at its outer end a pivotal connection with said uprights, wipers supported by the other end of the carrier, and means for raising the free end of the carrier and the wipers to impart updraw movements to the wipers.

8. A lasting machine having, in combination, a lasting head, swinging uprights rising from the head, a wiper carrier connected at one end to said uprights, wipers supported by the free end of the carrier, means for moving the carrier and wipers 60 forwardly, and means arranged to be actuated 65

ated by said movements to close the wipers to overwipe the upper into lasted position.

9. A lasting machine having, in combination, a wiper carrier, wipers supported thereon, wiper closing levers adapted to be 70 actuated by forward movements of said carrier to close the wipers to overwipe the upper into lasted position, and means for moving the wiper carrier upwardly and then forwardly to impart to the wipers successively updraw and overwiping movements. 75

10. A lasting machine of the class described, having, in combination, wipers, operating mechanism for the wipers, a retarder for holding the upper clamped against the upper face of the wipers, and means for imparting positive updraw, positive overwiping and positive closing movements to the wipers. 80

11. A lasting machine of the class described, having in combination, wipers, and operating mechanism for the wipers including connected means for positively imparting overwiping movements and downward compressing movements to the wipers. 85

12. A machine of the class described having, in combination, wipers mounted for upper stretching and overwiping movements, an actuating member, and operating 90 connections between the member and the wipers whereby upper stretching and overwiping movements are imparted to the wipers by movement of the actuating means in a single direction. 100

13. A lasting machine having, in combination, a wiper carrier supported for upward movement, wipers mounted on the carrier, a shaft, an eccentric on the shaft arranged to engage and raise said carrier and wipers, and means for operating the eccentric to 105 impart updraw movements to the wipers.

14. A lasting machine having, in combination, a wiper carrier supported for forward movement, wipers mounted on the carrier, a 110 shaft, an eccentric on the shaft arranged to move the carrier and wipers forwardly, means arranged to be actuated by said movement to cause the wipers to overwipe the upper into lasted position, and means for 115 operating the eccentric to impart the said overwiping movement to the wipers.

15. A lasting machine having, in combination, a wiper carrier supported for upward and forward movements, wipers mounted on 120 the carrier, a shaft, an eccentric on the shaft arranged to move said carrier and wipers upwardly and then forwardly, means arranged to be actuated by said forward movement to close the wipers, and means for operating the eccentric to impart said updraw and overwiping movements to the wipers. 125

16. A lasting machine having, in combination, a wiper carrier, wipers supported by the carrier and arranged to be actuated by 130

movement thereof to overwipe the upper and to press the upper down and compact it in lasted position, and means for imparting a yielding quality to said compacting action of the wipers.

17. A lasting machine having, in combination, a wiper carrier, wipers pivoted at their inner ends to said carrier, and means for supporting the front ends of the wipers 10 against downward movement relatively to said carrier.

18. A lasting machine having, in combination, a wiper carrier, wipers pivoted at their inner ends to said carrier, and means through 15 which force may be applied to the front ends of the wipers to press down and compact the overlasted margin of upper upon the sole.

19. A lasting machine having, in combination, a wiper carrier, wipers pivoted at their inner ends to said carrier, and means for supporting the front ends of the wipers against vertical movement relatively to said carrier comprising a pair of bearing arms 25 connected to the front ends of each of the wipers, and supporting members secured to said carrier and having their ends positioned between said bearing arms.

20. A lasting machine having, in combination, a lasting head, swinging uprights rising from said head, a bearing block carried by 30 said uprights, a wiper carrier having one end journaled in said block, a block for supporting the other end of said carrier, means for restraining said last named block from movement longitudinally of said carrier, a swinging upright rising from the head and pivotally connected at its upper end to said last named block, wipers supported by said 35 carrier, and means for moving said carrier and wipers forwardly to cause the wipers to overwipe the upper into overlasted position.

21. A lasting machine having, in combination, a lasting head, swinging uprights rising 40 from said head, a bearing block carried by said uprights, a wiper carrier having one end journaled in said block, a block for supporting the other end of said carrier, means for restraining said last named block from movement longitudinally of said carrier, a 45 swinging upright rising from the head and pivotally connected at its upper end to said last named block, a forked bracket on said last named upright, wipers supported by said carrier, and means arranged to engage said bracket for positively actuating said carrier and wipers forwardly to cause the wipers to overwipe the upper into lasted position.

22. A lasting machine having, in combination, a lasting head, uprights rising from the 50 said head, a bearing block supported by the uprights, a wiper carrier loosely journaled in the bearing block for movement about its longitudinal axis, and wipers mounted on 55 the carrier and arranged to be freely moved

by engagement with the work to turn the carrier about its said axis to permit the plane of the acting faces of the wipers to be made to coincide with the plane of the shoe bottom.

23. A lasting machine having, in combination, wipers, wiper closing levers, and a member having sliding connections with the rear ends of the said levers and supported for free movements transversely of the machine and shoe for positioning the wipers to 75 operate on lasts of crooked or unsymmetrical formation.

24. A lasting machine having, in combination, wipers, wiper carrying levers, and a member having sliding connections with the 80 rear ends of the said levers and supported for free movements transversely of the machine and shoe to enable each wiper to be automatically positioned by pressure thereof against the shoe for operating on lasts of 85 crooked or unsymmetrical formation.

25. A lasting machine having, in combination, wipers, wiper carrying levers that impart positioning movements and then overwiping movements to the wipers, and a member 90 having sliding connections with the rear ends of the said levers and supported for free movement transversely of the machine and shoe to cause the inward positioning movement of each wiper to be arrested at a point 95 determined by the position relatively to the median line of the machine occupied by the adjacent edge of the sole.

26. A lasting machine having, in combination, wipers that have positioning, updraw- 100 and overwiping movements, wiper carrying levers, and a member having sliding connections with the rear ends of the said levers and supported for free movement transversely of the machine and shoe to enable the 105 wipers to be positioned for operating on lasts of crooked or unsymmetrical formation, and means for thereafter automatically locking the said movable member in adjusted position comprising ratchets adapted to be 110 brought into locking engagement with said member during the updraw movement of the wipers.

27. A lasting machine having, in combination, a lasting head, uprights rising from 115 the head, a wiper carrier having one end pivotally supported by said uprights, and wipers supported by the other end of the carrier, said uprights having provision for permitting vertical adjustments of the carrier 120 for accommodating the plane of the wipers to the spring of the last.

28. A lasting machine having, in combination, wipers, mechanism adapted to be actuated for closing the wipers to overwipe 125 the upper into overlasted position, an actuator for said wiper closing mechanism, and means for adjusting said actuator means to vary the throw of the wipers for operating on shoes of different widths.

29. A lasting machine having, in combination, toe embracing wipers, a retarder comprising a thin curved plate of less curvature than the toe-bearing edgewise upon the upper to grip it upon the top face of the wipers, and means for operating the wipers and the retarder.
30. A lasting machine having, in combination, toe embracing wipers, and a retarder mechanism comprising a lever pivoted in front of the wipers and having a handle extending backwardly across the wipers and over the shoe bottom, a retarder depending from the lever between its pivot and the handle and mounted to yield upwardly, and a stop foot depending unyieldingly from the lever and engaging the upper overlaid upon the end portions of the wipers at the sides of the toe.
31. A lasting machine having, in combination, toe embracing wipers, and a retarder mechanism comprising a lever pivoted in front of the wipers and having a handle extending backwardly across the wipers and over the shoe bottom, a rigid stem depending from the lever, and a thin resilient plate on the lower end of the stem arranged to extend transversely across the shoe back of the end of the toe and clamp the upper yieldingly upon the top face of the wipers.
32. A lasting machine having, in combination, toe embracing wipers, means for producing relative movements of the last and the wipers in a direction perpendicular to the plane of the shoe bottom, and a retarder arranged to hold the upper on the wipers during said movement, said retarder being arranged to spread the upper from the sides of the toe forwardly over the wipers and hold it whereby forward drafting of the sides of the vamp is produced by said relative movement.
33. A lasting machine having, in combination, toe embracing wipers, means for producing relative movement of the last and the wipers in a direction perpendicular to the plane of the shoe bottom, and a retarder arranged to hold the upper on the wipers during said movement, said retarder being arranged to extend transversely of the end of the toe with its ends projecting beyond the opposite edges of the last in position to spread the upper.
34. A lasting machine having, in combination, toe embracing wipers, means for producing relative movements of the last and the wipers in a direction perpendicular to the plane of the shoe, and a retarder arranged to hold the upper on the wipers during said movement, said retarder comprising a member adapted to be brought downwardly to engage the upper at the end of the toe, and a stop adapted to extend transversely of the last to engage the upper at the corners of the toe to limit the extent of downward movement of the first named member.
35. A lasting machine having, in combination, toe embracing wipers, means for swinging the wipers inwardly and backwardly to overwipe the upper into lasted position, and a member arranged to hold the upper on the wipers at the corners of the toe during said movements, said member being restrained from partaking of the backward movement of the wipers.
36. A lasting machine having, in combination, toe embracing wipers, means for producing relative movement of the last and the wipers in a direction perpendicular to the plane of the shoe bottom, and a retarder arranged to hold the upper on the wipers, said retarder having a curvature less than the curvature of the toe end of the last for spreading the upper from the sides of the toe forwardly over the wipers and holding it whereby forward drafting of the sides of the vamp is produced by said relative movement.
37. A lasting machine having, in combination, toe embracing wipers, means for producing relative movement of the last and the wipers in a direction perpendicular to the plane of the shoe, and a retarder arranged to hold the upper on the wipers at the end of the toe with spring pressure during said movement whereby the tension exerted by the retarder upon the upper is automatically increased as said movement progresses.
38. A lasting machine having, in combination, wipers, wiper closing levers, links pivotally secured to said levers, a supporting band arranged to embrace the end of the shoe and having its ends passed around the free ends of the pivoted links, and springs having their inner ends connected to the ends of the band and secured at their outer ends to said levers, said springs operating to draw the ends of said band outwardly.
39. A lasting machine having, in combination, a wiper carrier, end embracing wipers, operating means for opening and closing the wipers, and means through which force may be applied to the front ends of the wipers to press down and compact the overlasted margin of upper upon the sole.
- In testimony whereof I have signed my name to this specification in the presence of two subscribing witnesses.

GUSTAF BERGMAN.

Witnesses:

HARLOW M. DAVIS,
FREDERICK L. EDMANDS.

It is hereby certified that in Letters Patent No. 1,168,470, granted January 18, 1916, upon the application of Gustaf Bergman, of Marlboro, Massachusetts, for an improvement in "Lasting-Machines," errors appear in the printed specification requiring correction as follows: Page 8, line 49, claim 6, for the word "of" read *or*; page 9, line 128, claim 28, strike out the word "means," second occurrence; and that the said Letters Patent should be read with these corrections therein that the same may conform to the record of the case in the Patent Office.

Signed and sealed this 2d day of May, A. D., 1916.

[SEAL.]

R. F. WHITEHEAD,

Acting Commissioner of Patents.

Cl. 12—14.
